UNITED STATES PATENT OFFICE.

ISRAEL J. FOLLY, OF WIOTA, IOWA.

ATTACHMENT FOR WINDMILLS.

No. 909,175.

Specification of Letters Patent.

Patented Jan. 12, 1902.

Application filed November 18, 1901. Serial No. 402,613.

To all whom it may concern:

Be it known that I, ISRAEL J. FOLLY, a citizen of the United States, residing in Wiota, county of Cass, and State of Iowa, have invented a new and useful Improvement in Attachments for Windmills, of which the following is a specification.

The object of my invention is to provide a wind wheel attachment for windmills in which the turntable will be anchored to the frame of the mill but capable of an easy rotary movement for throwing the wheel to the wind.

A further object is to provide a means of shifting the vane in which the wind wheel will greatly assist the operator.

Another object is to produce the said attachment in a construction which will be simple, strong, durable and comparatively inexpensive.

My invention consists of certain details of construction hereinafter set forth, pointed out in my claims and illustrated in the accompanying drawings in which—

Figure 1 shows a side elevation view of the top portion of a windmill, the wind wheel and vane being broken away; Fig. 2 shows a plan view of the same; Fig. 3 shows an enlarged detail view, in section, of the means of anchoring the turntable to the windmill; and, Fig. 4 shows a plan detail view of the same.

Referring to the accompanying drawings the reference numeral 10 is used to indicate the upper extremities of the uprights of a windmill to which is secured a circular plate 11 provided in its upper surface with a groove 12 designed to receive balls 13 adapted to be used as a bearing. The said plate 11 is anchored to the uprights 10 in any of the ordinary or usual methods.

The numeral 14 indicates the upper circular plate of my turntable provided in its under surface with a groove 15, similar to, and designed to operate in conjunction with, the groove 12 in securing the balls 13. The said plate 14 is provided with a flange 16, on its inner portion, and in this flange is secured the screw ends of bolts 17, which project downwardly to a connection with a plate 18 designed to project outwardly and to lightly engage the under surface of the plate 11. It is obvious that the plate 18 is adjustable and it is designed to operate as a bearing, or rather an anchor, for the entire

upper portion of my mill for the purpose of providing an engagement at all points on the turntable and thus prevent the said upper portion from blowing off the mill. It is equally obvious that the engagement of the plates 18 and 11 is so light as to permit of the easy movement of the plate 18 while the plate 11 remains stationary. The ball bearings 13 are designed to reduce friction in the movement of the upper plate 14 on the lower plate 11.

The numeral 19 indicates the shaft of the vane secured by any ordinary means, for movement in the arc of a circle from an upright beam or rod 20 and the numeral 21 indicates the stay rod of the said vane. Secured to the said shaft 19 is a downwardly projecting arm provided with a plate 22 at its lower extremity said plate being designed to engage the periphery of a flat wheel 23, rigidly secured to the rear of the shaft 24, which latter is secured to the wind wheel, said shaft 24 being anchored, or rather having its rear bearing on top of the upper surface of the plate 14. The said plate 22, by construction, is so located as to be out of engagement with the wheel 23 when the vane is in line with the shaft 24, but to be immediately brought into engagement with the periphery of the said wheel when the position of the vane is changed, relation being thereby had to the said shaft 24.

The numeral 25 indicates an arm projecting downwardly from and secured to, the shaft 19 and the numeral 26 indicates a second arm secured to the arm 25 and projecting outwardly at right angles therefrom.

The numeral 27 indicates a cable secured to the outer extremity of the arm 26 and projecting forwardly therefrom to a pulley mounted on a lug 28, cast on the outer portion of the plate 14, passing through said pulley and then inwardly and downwardly over a second pulley 29, mounted on lug 30 cast on the inner portion of the plate 14, and thence to the bottom of the windmill. This cable is designed as a means for shifting the position of the vane, with relation to the wind wheel, and to thus throw the wind wheel out of engagement with the wind, and stop the operation of the mechanism. It is obvious that by pulling the said cable the shaft 19 will be operated, to move in the arc of a circle, from its bearings with the beam or rod 20 and it is equally obvious that the plate 22 engaging

and riding on top of the wheel 23 will cause the rotation of said wheel to assist in moving the said vane. By construction the arm 26 is of such a length as will cause it to come in contact with the lug 28 when the vane is at right angles to the shaft 24 and it is obvious that this will retard any further movement of the said vane. The cable is then secured below. I have also provided a coil spring 31, secured to the shaft of the vane and the upper portion of the plate 14, designed to hold the vane in position while the mill is operating and to also throw the vane into proper position, when the wind wheel is desired to be thrown to the wind.

Having thus described my invention what I claim and desire to secure by Letters Patent of the United States is;

1. In a wind mill, an upper annular plate and a lower annular plate spaced therefrom, balls between said plates, an inwardly projecting horizontal flange rigid with one of said plates, a horizontal plate engaging the other of said annular plates, and vertical fas-

tening means passing through said horizontal plate and secured to said flange.

2. In a wind mill including a turntable at its top, a drive shaft disposed above said turntable, a flat surfaced wheel rigidly secured to said drive shaft, a horizontal vane supporting shaft, an arm projecting downwardly from said last named shaft, a plate secured to the lower end of said arm for engagement with the periphery of said wheel, and means for moving said vane supporting shaft in the arc of a circle.

3. In a wind mill, a vane supporting shaft, an arm depending from said shaft, a rod secured to said arm at its lower end and at right angles thereto, a turntable including a top plate, oppositely disposed lugs on said plate, a pulley on each lug, and a cable connected to the free end of said rod and extending over each of said pulleys.

ISRÄEL J. FOLLY.
